UNITED STATES PATENT OFFICE.

AUGUST ERNST FIEDLER, OF CHEMNITZ, SAXONY, GERMANY.

SKATE.

SPECIFICATION forming part of Letters Patent No. 429,266, dated June 3, 1890.

Application filed November 4, 1889. Serial No. 329,160. (No model.) Patented in Germany March 5, 1889, No. 49,695, and September 23, 1889, No. 51,056, and in Austria-Hungary October 10, 1889, No. 44,215 and No. 67,012.

To all whom it may concern:

Be it known that I, AUGUST ERNST FIEDLER, a subject of the Emperor of Germany, and a resident of Chemnitz, Saxony, Germany, have 5 invented a new and useful Improvement in Skates, (for which I have obtained patent in Germany, No. 49,695, March 5, 1889, and No. 51,056, September 23, 1889, and in Austria-Hungary, No. 44,215 and No. 67,012, October 10, 1889,) of which the following is a specification.

This invention relates to an improvement in skates, and has for its purpose to provide an effective device for rendering the step of 15 the person using the skate more elastic both vertically and lengthwise than is the case in the skates hitherto known.

Referring to the accompanying drawings, Figure 1 is a side view and partial section; 20 Fig. 2, a plan of a skate embodying the improvement. Fig. 3 is a cross-section of the improved device along line A B, Fig. 1.

The plate *c*, secured on spring *d*, which bears on rail or cheek *a* and is pivoted at *g*, 25 is provided with a slot *h*, in which is displaceable the quadrangular block *k*. Through the latter passes a pin *z*, connected at the top with foot-rest *b*, and having at its lower extremity a screw-thread for receiving the nut *m*.

Around pin *z* and between block *k* and nut *m* a helical spring *l* is provided, which tends to press the block *k* in an upward and the foot-plate *b* in a downward direction against plate *c*.

To foot-plate *b* are secured clamps *e' e²*, adjustable by means of screws *s' s²*, and serving to be firmly pressed against the sides of the sole, thereby causing foot-plate *b* to adjust itself around pin *z* to the shape of the sole.

The above-described disposition of block *k* enables the foot-rest *b* to slide to and fro in the slot *h*, thereby compensating the elastic up-and-down movement of the plate *c*.

What I claim is—

In skates, a device for rendering the step 45 of the skater elastic, consisting of a sole-rest *b*, having adjustable clamps *e' e²*, in combination with pin *z*, slotted plate *c*, elastic plate or bow *d*, block *k*, helical spring *l*, and nut *m*, substantially as specified.

In testimony whereof I have signed this specification in the presence of two subscribing witnesses.

AUGUST ERNST FIEDLER. [L. s.]
